SNAP FASTENER

John H. Ohotto, Bowlus, Minn.

Application May 8, 1940, Serial No. 334,056

3 Claims. (Cl. 24—241)

This invention relates to snap fasteners for animal harnesses and other similar devices, and has for the primary object the provision of a durable, inexpensive and efficient device of this character which will be extremely easy and simple to open and close and which will not accidentally open during its use as a fastening medium and will only open when manually actuated in a proper manner and will not readily catch into objects when in use.

With these and other objects in view which will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

20 Figure 1 is a side elevation illustrating a snap fastener constructed in accordance with my invention.

Figure 2 is a side elevation showing the snap fastener in an open position.

25 Figure 3 is a side elevation, partly in section, showing the snap fastener in a closed position.

Figure 4 is an end view illustrating the snap fastener.

Figure 5 is a sectional view taken on the line 30 5—5 of Figure 2.

Figure 6 is a sectional view taken on the line 6—6 of Figure 2.

Referring in detail to the drawing, the numeral 5 indicates as an entirety a snap fastener including a bill portion 6, an eye 7, a straight shank 7' and a combined closure element and fastening device 8. The bill portion, eye 7 and shank 7' are constructed from a single length of cylindrical stock.

The stock is first bent upon itself to form 40 the eye 7, the latter being closed by a quarter twist of the stock about itself. The stock after forming the eye and the twist is bent to provide the bill portion 6 and the shank 7'. The bill portion includes a part A which parallels the shank

45 7' and is spaced therefrom. The bill portion further includes a portion B having a compound curvature thereto forming offsets C and D. The offset C is for the purpose of receiving a ring or the like which may be applied to the bill portion

50 for supporting the ring out of the path of movement of the combined closure element and fastening medium 8, as clearly shown in Figures 1 to 3, inclusive.

The closure element includes a tubular sleeve 55 9 slidably mounted on the shank 7' and is pro-

vided in opposite sides thereof with slots 10 through which extends a pin 11 secured in the shank 7'. Integral with one end of the sleeve 9 and extending at substantially right angles thereto is a tongue 12 having a compound curvature thereto providing an offset portion 13 to fit in and conform to the offset D of the bill portion 6. The tongue opposite to the offset portion 13 has an arcuate curvature thereat, as shown at 14, on which the ring or other device applied to the bill portion may ride when the snap fastener is in use, acting to retain the tongue in engagement with the bill portion. The tongue has a channel 15 formed therein to receive a part of the bill portion and the free end of the latter, as clearly shown in Figure 3.

Surrounding the shank 7' is a coil spring 16, one end of which seats against the sleeve 9 while the opposite end seats against an end flange 17 of a restraining sleeve 18 which may slide over the sleeve 9. The spring forces the flange 17 of the sleeve 18 in engagement with a stop 19 on the shank 7'.

When the sleeve 18 or the flange 17 thereof is in seated engagement with the stop 19 and the tongue 12 of the fastening element in engagement with the bill portion, the spring is under a very slight tension so that when desiring to open the snap fastener, a person may readily move the sleeve 9 endwise on the shank 7' against the tension of the spring to disengage and space the tongue 12 from the bill portion, as clearly shown in Figure 2. This opens the snap fastener to its fullest extent so that it can be applied and removed in any extremely easy manner.

The sleeve 18 has formed in opposite sides thereof bayonet slots 20, portions of which are in the form of grooves pressed in the sleeve. The slots receive the pin 11 and when the closure element is in a position of engaging the bill portion and the sleeve 18 moved in the direction of the tongue 12 and given a slight rotation, the pin will move into the lateral branches of the bayonet slots securing the sleeve 18 in the position shown in Figure 1, whereby the spring 16 will be put under extremely severe compression increasing its action of forcing the tongue 12 of the fastening element into engagement with the bill portion of the fastener, and which will prevent the fastening element from being moved or slid on the shank 7' to disengage the tongue from the bill portion, consequently preventing opening of the snap fastener.

An offset 21 is formed on the sleeve 9 to permit a person to place a thumb or finger thereon for

imparting sliding movement to the sleeve 8 against the action of the spring.

While I have shown and described the preferred embodiment of my invention, it will be understood that minor changes in construction, combination and arrangement of parts may be made without departing from the spirit and scope of the invention as claimed.

Having thus described the invention, what I claim is:

1. In a snap fastener of the class described, a bill portion including a compound curvature to provide spaced indentations, an eye integral with the bill portion, a shank integral with the eye, 15 a sleeve slidable on the shank and having a slot, a pin carried by the shank and extending through the slot, a tongue integral with the sleeve and extending at an angle thereto and including an indentation to engage one of the indentations of 20 the bill portion and having a groove to receive a part of the bill portion and its free end.

2. In a snap fastener of the class described, a bill portion, an eye integral with the bill portion, a shank integral with the eye, a sleeve slid able 25 on the shank and having a slot, a pin carried by the shank and extending through the slot, a tongue integral with the sleeve and extending at an angle thereto to engage and close the bill portion, a second sleeve slid able on the shank and receiving therein the first sleeve and having a bayonet slot to receive the pin, a stop for lim- 30

iting the sliding movement of the second sleeve in one direction, and a coil spring mounted on the shank and engaging the first and second sleeves to urge the first sleeve in the direction of engaging the tongue with the bill portion and adapted to have its tension increased and decreased by the position of the second sleeve on the first sleeve.

3. In a snap fastener of the class described, a bill portion, an eye integral with the bill portion, a shank integral with the eye, a sleeve slid able on the shank and having a slot, a pin carried by the shank and extending through the slot, a tongue integral with the sleeve and extending at an angle thereto to engage and close the bill portion, 10 a second sleeve slid able on the shank and receiving therein the first sleeve and having a bayonet slot to receive the pin, a stop for limiting the sliding movement of the second sleeve in one direction, a coil spring mounted on the shank and 15 engaging the first and second sleeves to urge the first sleeve in the direction of engaging the tongue with the bill portion and adapted to have its tension increased and decreased by the position of the second sleeve on the first sleeve, said 20 bill portion including a compound curvature to provide spaced indentations, said tongue including an offset to engage in one of the indentations, said tongue having a groove to receive a part of the bill portion and its free end.

JOHN H. OHOTTO.
